UNITED STATES PATENT OFFICE.

ARTHUR FAGERLUND AND EMIL SUNILA, OF BROOKLYN, NEW YORK.

CONCRETE-MOLD.

1,268,704.

Specification of Letters Patent. Patented June 4, 1918.

Application filed August 21, 1917. Serial No. 187,344.

To all whom it may concern:

Be it known that we, ARTHUR FAGERLUND, a citizen of Finland, and EMIL SUNILA, a citizen of the United States, both 5 residents of the city of New York, borough of Brooklyn, in the county of Kings and State of New York, have invented a new and Improved Concrete-Mold, of which the following is a full, clear, and exact description.

This invention relates to concrete molds and has for an object the provision of an improved construction of mold designed for molding columns and the like in concrete 15 buildings or separately.

Another object in view is the provision of a mold formed from sheet metal and arranged with means whereby the thickness of the mold may be readily adjusted.

20 Another object of the invention is to provide a mold with means for adjusting the depth and means for adjusting the connection between the head and the main part of the mold whereby the same ornamental head 25 may be produced on both large and small columns.

A further object of the invention is the provision of an improved arrangement of identical braces for holding the mold in a 30 vertical position and for adjusting the same accurately.

A still further object of the invention is the provision of bracing means or frames for holding the body of the mold in proper 35 position.

In the accompanying drawings:—

Figure 1 is a rear view of the upper end of two molds and certain bracing means embodying the invention.

40 Fig. 2 is a transverse sectional view through Fig. 1 on line 2—2.

Fig. 3 is an edge view of one of the molds shown in Fig. 1.

Fig. 4 is a front view of the mold shown 45 in Fig. 3.

Fig. 5 is a sectional view through Fig. 6 on line 5—5.

Fig. 6 is a top plan view of the mold shown in Fig. 3.

50 Fig. 7 is a bottom plan view of the adjusting mechanism and of parts of the adjusting mechanism, the same being taken approximately on line 7—7, Fig. 4.

Fig. 7^a is a bottom plan view of an adjusting mechanism embodying certain features of the invention, the same being taken

through Fig. 4 approximately on line 7—7.

Fig. 8 is a sectional view through Fig. 7^a on line 8—8.

Fig. 9 is a fragmentary perspective view 60 of a supporting structure embodying certain features of the invention.

Referring to the accompanying drawings by numerals, 1 indicates a mold or form for casting concrete columns, said form being 65 held in proper shape by the bracing frame

2. The mold 1 may be shaped in cross section as shown in Fig. 3, may be shaped square or may be shaped in slightly modified ways without departing from the spirit 70 of the invention, and continually permitting the frames 2 to hold the front, back and sides in proper position. As shown in Fig.

2 the back plate 3 is flat while the front plate 4 is curved or rounded and is connected 75 by bolts 5 to the sides 6 and 7, said sides being flat. All of the parts are preferably made from sheet metal and, consequently, the frames 2 are necessary to hold the parts in proper shape while the concrete is setting. 80

The side plates 6 and 7 are provided with a number of apertures for accommodating bolts 5, as shown in Fig. 3, whereby the front plate 4 may be in the position shown in Fig. 2 or the dotted position shown in 85

Fig. 2, as well as in other positions, so as to vary the thickness of the column from front to rear.

In concrete structures, especially in concrete buildings provided with columns, it is 90 customary to provide a comparatively large column on the ground floor and smaller columns on the upper floors, the smallest being on the top floor. In order to carry out this idea and to scientifically reduce the amount 95

of weight to be carried, the front plate 4 is moved toward the rear plate 3 on each

floor and thereby reduces the thickness of the column without affecting the width. In

order to produce proper shaped corners at 100

the rear, corner members 8 and 9 are provided having flanges 10 and 11 accommo-

dating bolts which pass through the flanges

and through the back plate 3 and the side

plates 6 and 7, respectively. The side plates 105

6 and 7 are cut away at 12 and 13 in order

to allow a wrench to be inserted when apply-

ing or removing the bolts 14 and 15.

As above mentioned, the frames 2 are pro-

vided for preventing any outward movement 110

of the plates when properly adjusted. These

frames are made up of bars 16, 17, 18 and

19, bar 16 having turned over hooks 20 and 21 at the ends while the bars 17 and 19 have hooks 22 and 23 at one end of the respective bars and apertures 24 and 25, respectively, 5 at the opposite end. A pin extends through each end of the bar 18 and through one of the apertures 24 and 25, respectively, for holding the bar in any position, as for instance, that shown in Fig. 2. The hook ends 10 of the bars 17 and 19 overlap bar 16 whereby the various wedges 26, 27, 28 and 29 may be used and caused to press the bars against the side plates and the back plate continually and hold the same in this position during 15 the casting and setting of the concrete. After the column has been properly set and it is desired to remove the form it would be difficult to take the pins or bolts out of bar 18 and apertures 24 and 25 without loosening 20 the frames 2. By constructing the wedges 26 to 29, inclusive, as shown in Fig. 2, the loosening action may be provided by driving these wedges out, whereupon the frame may be readily removed and after 25 ward the bolts 14 and 15 removed. This will allow the various plates of the mold to be slipped from the column.

In order to provide a proper spacing and reinforcing member for the frames 2 an 30 angle bar 30 is provided, which may be secured directly to the various bars 16, as shown in Fig. 2, while a steadyng bar 31 is connected by a bolt or otherwise to the upper end of bar 30, as shown in Fig. 1. The bar 35 31 extends horizontally from one form to the other in order that the upper end of the various forms may be properly spaced apart and held against side movement. A suitable diagonal brace 32 (Fig. 3) is provided 40 for preventing the form from swaying toward the front or toward the back, as hereinafter fully described. In this way the forms are properly maintained in position for casting during the setting operation while 45 allowing a ready removal after the column has set. It will be noted that all the parts may be applied and removed without injury so that the molds or forms may be used over and over.

50 As above stated, the columns in a building are of different sizes, the smaller sizes being arranged at the top and the larger sizes at the bottom. The heads of the columns, however, are preferably the same size throughout, and in order to provide a proper head 55 a sheet metal form 33 is provided, as shown in Fig. 5, which is held in a given shape by the bands 34 and 35 which are readily secured to the various strips of metal making 60 up the head. Suitable reinforcing T bars 36 are also provided, as shown in Fig. 4, for bracing the sheets forming the head. In order to cause the concrete casting to merge into the main column an apron 37 is provided, formed of a plurality of plates con-

nected by bolts 38 to the head 33. The plates 39 are adjusted by reason of the fact that each plate is pivotally mounted on one of the bolts 38 and is allowed to move by reason of the slot 40 though subject to be 70 clamped in any adjusted position. By providing an adjustable apron of this kind for the head 33 the column will properly merge into the cast head and, consequently, will produce a complete column. The head 33 75 with the apron 37 is removable and ordinarily rests against the upper edge of the plates 3, 4, 6 and 7 and is held against tilting movement by suitable guy members 41 and 42, said guy members being of substantially guy structure, as for instance, a guy wire provided with a turn-buckle 43 whereby an easy adjustment is provided.

In setting up the molds it is oftentimes more or less difficult to have the same perfectly vertical, and in order to provide an easy adjustment of the parts for causing the molds to be absolutely vertical a diagonal brace 32 is provided which is connected with a rod 44, as shown in Figs. 4, 7^A and 8. The 85 rod 44 is preferably somewhat loosely fitted into the end of the brace 32 and is pivotally mounted at 45 to the top frame 2. This top frame carries at the end a fitting 46 formed substantially U shape as shown in Fig. 7, 90 said fitting being of metal and provided with a slot 47 through which the rod or bar 44 extends. The rod 44 is provided with a nut 48 which is rigidly secured thereto, and which accommodates the threaded rod 48', 100 said rod extending through slots 48 at each side of the frame 2 as shown in Fig. 7, so that when the rod 48' is held by a wrench or other member engaging the square ends of the rod nut 48 will be moved and consequently the rod or bar 44 will be moved so as to shift the position of frame 2 and consequently the position of the upper end of the entire mold. The frame 2 shown in Fig. 7 and also in Figs. 3 and 4 is made from 110 metal, but as disclosed in Fig. 7^A and Fig. 8 the U-shaped member 46 may be secured to a wood frame 2', the parts operating as just described. This will allow the adjusting mechanism to be applied to wood frames 115 now in common use as the U-shaped fitting 46 may be nailed or otherwise rigidly secured either to a wood frame or to an extension and a proper adjustment secured in a similar manner to the way the steel or iron 120 frame it adjusted.

It will be noted that the forms are made from sheet metal, but it is to be understood that other materials, as for instance, wood, may be used without departing from the 125 spirit of the invention. It is also to be understood that the diagonal bracing member 32, the rod 44 and associated parts for adjusting the vertical position of the mold may be used with wooden molds, metallic 130

molds or molds made from any material without departing from the spirit of the invention.

When casting a number of columns the forms are arranged preferably as shown in Fig. 1, with the connecting rod 31 which is connected to the vertical reinforcing bars 30 in any suitable manner, as shown in Figs. 1 and 2, said reinforcing bars thereby reinforcing the rear of the column and at the same time providing means in connection with bar 31 for holding the forms properly spaced. The supporting structure shown in Fig. 9 is built up around each column and the ring or band 73 is caused to engage the angle iron 34. This will hold the head against the ceiling as shown in Fig. 4 so that the finished column will extend up to and merge into the ceiling.

20 What we claim is:

1. In a mold of the character described, a sheet metal casing formed with side plates, a bowed front plate, adjustable means for connecting the edges of the bowed front plate to the side plates, a back plate, corner plates at the rear, removable means for holding said corner plates in position, and a surrounding reinforcing frame for holding all of said plates in their correct position.

2. In a mold of the character described, a pair of side plates formed with rows of apertures, a back plate, a front plate, a plurality of bolts extending through each edge of said front plate and through some of the apertures in said side plates, said apertures permitting an adjustment of the front plate toward and from the rear plate, a corner plate connected near each edge of said rear plate, and a reinforcing frame arranged exteriorly of said plates.

3. In a mold of the character described, a rear plate, a front plate, a pair of side plates, means for adjustably connecting the edges of the front plate with the side plates whereby the front plate may be arranged at different distances from the rear plate, each of said side plates being spaced from the rear plate, a corner plate connected with said rear plate and said side plates and spacing the opening between the rear plate and the side plates, means for removably clamping the corner plates in position, said means being made easy of access by reason of the space between the side plates and the rear plate, and a surrounding bracing member for all of said plates.

4. In a mold of the character described,

a front plate, a back plate, side plates, a plurality of reinforcing frames arranged at 60 different points along said plates, each of said frames comprising four bars, one of said bars having an inclined hook at each end while the second of said bars is provided with an opening at each end and the 65 remaining bars are provided with a plurality of openings at one end and hooks at the opposite end, wedges arranged in each of said hooks for pressing the bars against said plates, and a pin extending through 70 each end of the second mentioned bar and some of said openings so as to lock the bars in the adjusted position.

5. In a mold of the character described, a form for receiving concrete, a diagonal 75 brace for holding the form in an upright position, means connecting the diagonal brace and form, said means comprising a member pivotally mounted to the form and loosely connected with the brace, and an 80 adjusting member on the form engaging said pivotally mounted member so as to shift the form back and forth in either of two directions for causing the form to assume a perfectly upright position. 85

6. In a mold of the character described, a plurality of plates forming a hollow mold structure, a removable head mounted on said plates, said head having a flaring upper part, and a plurality of adjustable members 90 acting as an apron for causing the lower part of the head to conform to the shape and size of the mold formed of said plates, and means for holding said plates in a given position. 95

7. In a mold of the character described, a form for receiving concrete, a diagonal brace for holding the form in an upright position, means connecting the diagonal brace and form, said means comprising a 100 member pivotally connected with said form and articulated with said brace, a nut connected with said pivotally mounted member, an adjusting threaded member extending through said nut and engaging the threads 105 thereof, and means for holding said threaded member against longitudinal movement while allowing a radial movement whereby the form may be shifted back and forth in either of two directions upon the rotation 110 of said threaded member for causing the form to assume a perfectly upright position.

ARTHUR FAGERLUND.
